CLOSURE FOR COTTON GIN ROLL BOXES

John Blewett, Dallas, Tex., assignor to The Murray Company, Dallas, Tex., a corporation of Texas

Application September 16, 1935, Serial No. 40,703

7 Claims. (CL. 19—55)

This invention relates to new and useful improvements in closures for cotton gin roll boxes.

One object of the invention is to provide an improved closure for the roll box of a cotton gin which is arranged to permit ready access to the interior of the box when it is necessary to clean the ginning ribs, or for any other reason.

An important object of the invention is to provide an improved closure for the front of the roll box of a cotton gin which is arranged to be hinged at either its upper or lower end whereby it may be swung either from its upper or lower end, and also being so constructed that it may be completely removed to open the entire front of the roll box.

Still another object of the invention is to provide an improved closure for the front of a roll box which is supported by retractile pins at its upper and lower ends, whereby when the upper pins are retracted the closure may be swung downwardly with the lower pins as a pivot, and when the lower pins are retracted, said closure may be swung upwardly, the upper pins serving as a pivot, the location of the pins being such that a single operator can operate the closure; the retraction of both upper and lower pins permitting the entire closure to be readily removed.

Still another object of the invention is to provide a swinging closure for the front of a roll box which is constructed so that when opened the roll within the box may be retained, the hinge of said closure being such that the seed within the box can not enter beneath the open closure to prevent complete closing of the same.

A further object of the invention is to provide an improved closure for the roll box of a cotton gin having retractile means for holding the same in a closed position, said retractile means being arranged to engage the gin frame, when the lower end of the closure has been swung to an open position, said means thereby holding said closure in such open position.

A still further object of the invention is to provide an improved closure for a roll box which is mounted on retractile pins engaging the gin frame, whereby all bolts, nuts and other holding means which necessitate the use of tools are eliminated.

A construction designed to carry out the invention will be hereinafter described, together with other features of the invention.

The invention will be more readily understood from a reading of the following specification and by reference to the accompanying drawings, in

which an example of the invention is shown, and wherein:

Figure 1 is a transverse, vertical sectional view of a cotton gin, having a closure constructed in accordance with the invention, closing its roll box,

Figure 2 is a longitudinal, vertical sectional view, taken on the line 2—2 of Figure 1,

Figure 3 is an isometric view of one end of the closure,

Figure 4 is an enlarged detail view of one of the retractile pins and its mounting,

Figure 5 is an isometric view of one of the pins, and

Figure 6 is a transverse, vertical sectional view of the closure showing the same swung downwardly, the other positions of said closure being shown in dotted lines.

In the drawings, the numeral 10 designates an ordinary cotton gin which may be of the usual construction. The gin has the usual outer pivoted gin breast 11, ginning saws 12, ginning ribs 13 and huller ribs 14. The roll box A is formed above the ginning saws and ribs in the usual way. The front of the gin breast 11 is removable and is generally known as the outer front. The front of the roll box is usually closed by an inner front which is removable also so as to permit access to the interior of the roll box.

The removal of the outer and inner fronts entails considerable time in loosening bolts and nuts to permit such removal. Many times, it is only necessary to reach within the roll box to remedy the particular trouble and therefore, the necessity of the removal of the inner front results in a waste of time.

In carrying out the invention, the usual front which closes the roll box A is eliminated, and a curved closure 15 is provided. This closure extends transversely within the gin breast between the side walls 16 thereof, and, as clearly shown in Figures 2 and 3, is formed of a pair of curved, flanged end members 17, which are constructed of metal or other suitable material. The end members are preferably cast but may be constructed in any desired way.

A curved plate 18 extends between the members and has its upper and lower ends bent upon itself to form elongated channels 19 at the upper and lower ends of said plate. A complementary outer plate 20 is welded or otherwise secured to the plate 18 and overlies the same. As clearly shown in Figure 3, the outer plate serves to retain the ends of the inner plate in their bent position. Both plates are then secured to the end

members 17 by rivets, or other means, whereby an elongated curved closure for the roll box A is formed. If desired, the outer plate 28 may be bent upwardly to form a longitudinal rib 21 throughout its length, whereby rigidity will be added to the structure.

For mounting the closure between the side walls 16 of the gin breast 11, an elongated, tubular casing 22 is inserted in the upper channel 10 19 of the sheet 18. The ends of the casing terminate adjacent the side flanges 17' of the end members 17 of the closure (Figure 2), and the casing is suitably fastened in the channel. It may have a tight fit and be driven therein.

15 A plunger 23 is mounted at each end of the casing and is slidable therein. The outer end of each plunger is formed with a reduced pin 24, whereby an annular shoulder 25 is provided. The reduced pin extends from the end of the casing 20 and passes through an opening 26 (Figure 4) in the side flange 17' of the end member 11. The extreme outer end of said pin is arranged to engage in an opening 27 formed in the side wall 16 of the gin breast.

25 The pin is normally held in engagement with said opening, with the annular shoulder 25 about the inner side of the flange 17' by a coiled spring 28 which is confined within the casing 22 between the inner end of the plunger 23 and a transverse pin 29 which extends across said casing. Thus, it will be obvious that the springs exert their pressure to hold the plungers in their outer positions (Figure 2) with the reduced pins 24 engaging in the openings 27 in the side walls of the gin breast. The engagement of the annular shoulder 30 25 of each plunger with inner side of the flange 17' prevents the displacement of said plunger from the casing. It is noted that when the pins are within the openings 27, the upper end of closure 35 is attached to the breast 11.

40 For locking the pins within the openings, each plunger 23 is provided with a radially extending thumb bolt 30 which projects outwardly and is slidable within a slot 31 (Figure 3) formed in the outer side of the channel 19. The slot is provided with offset notches 32 at each end thereof and the bolt 30 is so located on the plunger that when the pin 24 is engaging in the opening 27, said bolt is opposite the outer notch 32. A slight rotation 45 of the plunger causes the bolt to enter said notch, and it will be seen that said plunger cannot be moved to disengage the pin from the opening 27 until such time as the thumb bolt is moved from said outer notch.

50 When said bolt is disengaged from the outer notch, the plunger may then be slid inwardly under tension of the coiled spring 28, and after the pin 24 is retracted from the opening 27, the thumb bolt may be swung into the inner offset 55 notch 32, whereby the plunger may be locked in a retracted position.

55 From the above, it will be seen that the upper end of the closure is supported in the side walls of the gin breast 11, by the retractable plungers 60 23. The lower end of said closure is supported by similar plungers 23' which are mounted in the ends of a casing 22' located within the lower channel 19. These plungers are provided with reduced pins 24' which engage openings 27' in the side walls of the gin breast. The construction and operation of the lower plungers are exactly the same as the upper pins and a detailed description would merely be repetition. Corresponding parts of the lower plungers have been 65 given prime numbers.

It will be seen that the closure is mounted between the side walls of the gin breast to close the front of the roll box A. With the upper plungers 23 and the lower plunger 23' in their outer positions, the pins 24 and 24' engage their respective openings 27 and 27' in the side walls 16. Assuming the thumb bolts 30 and 30' to be engaged in the offset notches, it will be seen that the closure is securely locked in position.

10 In ginning wet cotton, or under other conditions, the ginning ribs 13 may become clogged and it is necessary to reach within the roll box A to clean said ribs. It is only necessary, after the outer front of the breast 11 has been removed, for the operator to grasp the thumb bolts 30, one 15 in each hand, and retract the upper plunger 23 to disengage the pins 24 from the openings 27. The lower pins 24' are still in engagement with their respective openings, and the closure may then be swung to the position shown in dotted 20 lines in Fig. 1 and in full lines in Figure 6. It is noted that the pins 24' serve as the pivot on which said closure swings.

The operator may then move the entire roll within the box A forwardly onto the inner side 25 of the closure and the ginning ribs and saws are then readily accessible. When it is desired to close the closure, the upper end is swung inwardly. Due to the curve of the inner side of said closure and also to the fact that the closure is 30 hinged on the pins, any seed which might have accumulated on the inner face of said closure while the same was open, will fall from said closure as it moves to a closed position. It is noted that there is no possibility of the accumulated seed 35 interfering with the closing by falling into the hinge, as is the case in some closures now in use. The curve of the closure positively guides the seed- 40 back into the roll box.

In some cases, it is desirable to swing the closure upwardly completely out of the operator's way so that the interior roll box is easily accessible. In such cases the upper plungers 23 remain in their outer position so that their pins 24 remain within their respective opening 27 in the 45 side walls 16. The lower plungers 23' are retracted so that their pins 24' are disengaged from the openings 27', so that the closure may be swung upwardly as shown by dotted lines in Figure 6.

If desired, after the lower end of the closure 50 has been swung above the top of the side walls 16 the plungers can be again moved outwardly so that the pins 24' rest upon the top edge of said side walls to prevent downward movement of the closure until such time as the plungers 23' are 55 again retracted. It is noted that this action is automatic if the thumb bolts 30' are not engaged with the inner offset notch 32' when the plungers 23' are first retracted to disengage the pins 24' from the openings 27', for it is obvious that during the upward swinging, the outer edge of the pins 24' will ride against the inner side of the walls 16, being held so by the coiled springs 28'. As soon as the pins clear the upper end of said walls, said spring will immediately move them 60 outwardly.

65 From the above, it will be seen that the closure may be either swung upwardly or downwardly depending on whether the upper or lower pins are retracted from their respective openings. If the upper pins are retracted, the lower pins form the hinge, and vice versa. The disengagement of the pins may be readily accomplished by one operator who can grasp one of the thumb bolts 70 in each hand and swing the closure. Hereto- 75

fore, the removal of the front of the roll box required at least two men. The swinging from either the top or bottom of the closure permits ready access to the interior of the roll box A for any purpose.

In some cases, it is desirable to entirely remove the closure, and when this is necessary, both sets of pins 24 and 24' are retracted from the openings and the entire closure may be removed. It is noted that the closure is fastened in place by the retractile pins which may be easily operated by hand. No nuts, bolts, or other comparatively permanent means is employed. This eliminates the use of any kind of tools and saves a great deal of time and labor on the part of the gin operator.

It is noted that the particular structure of the closure is subject to variation and it is not necessary to make the closure of the end members and plates, but all these parts could, if desired, be made integral. It is further pointed out that the closure may be attached to any ordinary cotton gin having the roll box A above the ginning saws and ribs.

25 What I claim and desire to secure by Letters Patent is:

1. A closure for the roll box of a cotton gin including, a curved member extending longitudinally across the front of said roll box to close the same, retractile locking means resiliently biased toward their locking position carried by the upper end of the member and engaging the walls of the gin breast for pivotally supporting the upper end of the same, and similar retractile locking means resiliently biased toward their locking position for pivotally supporting the lower end of the member, and means independently operable for retracting both the upper and lower retractile means, whereby the member may be either swung downwardly from its upper end or swung upwardly from its lower end, or may be entirely disengaged from the breast, the curve of the member being such that when the upper means has been retracted to permit downward swinging of the member, the seed within the roll box is prevented from entering the hinge of the member, whereby interference by the seed with the closing of said member is eliminated.

2. A closure for the roll box of a cotton gin including, a curved member extending longitudinally across the front of said roll box to close the same, retractile means carried by the upper end of the member and engaging the walls of the gin breast for pivotally supporting the upper end of the same, and similar retractile means for pivotally supporting the lower end of the member, and means for retracting both the upper and lower retractile means, whereby the member may be either swung downwardly from its upper end or swung upwardly from its lower end, or may be entirely disengaged from the breast, the curve of the member being such that when the upper means has been retracted to permit downward swinging of the member, the seed within the roll box is prevented from entering the hinge of the member, whereby interference by the seed with the closing of said member is eliminated, the location of the lower retractile means being such that when the member is swung upwardly, said means will engage the upper edge of the side walls of the gin breast to hold said member in an open position.

3. A closure for the roll box of a cotton gin including, a closure member extending longitudinally between the end walls of the gin breast across the front of said roll box to close the same, a pair of spring-pressed plungers at the upper opposite corner portions of said closure member and extending outwardly from the ends thereof for engaging in openings in said end walls to support the upper end portions of the member, similar spring-pressed plungers at the lower corners of the member for engaging openings in the walls of said gin breast to support the lower end portions of the member, means on each plunger for retracting the same to disengage it from its opening, and means for releasably retaining the plungers in their extended and retracted positions.

4. A closure for the roll box of a cotton gin including, a longitudinally extending member arranged to close the forward end of said box, separate retractile means for supporting the upper opposite corner portions of said member, separate retractile means for supporting the lower opposite corner portions of said member, and means for releasably retaining said retractile means in either their extended or retracted positions.

5. A closure for the roll box of a cotton gin including, a removable closure member extending longitudinally between the end walls of the gin breast across the front of said roll box to close the same, separate retractile means on said closure member engaging the walls of the gin breast for pivotally supporting the upper end of the member, similar retractile means for pivotally supporting the lower opposite corner portions of the member, whereby either the upper or lower means may be retracted at will to permit the closure member to be swung either upwardly from its lower end or downwardly from its upper end, and means for releasably retaining said retractile means in either their extended or retracted positions.

6. A closure for the roll box of a cotton gin including, a removable closure member extending longitudinally between the opposite end walls of the gin breast across the box to close the same, and retractile independently operable locking means mounted on each end corner portion of said closure member and resiliently projected into supporting engagement with the contiguous end wall portions of the gin breast whereby to releasably lock said member in place and to hingedly support said member near either longitudinal side when the locking means near the opposite longitudinal side is retracted from engagement with the wall portions of the gin breast.

7. A closure for the roll box of a cotton gin including, a removable closure member extending longitudinally between the opposite end walls of the gin breast across the box to close the same, and separate retractile and independently operable bolts mounted on the opposite end corner portions of the closure member and being spring-pressed and normally urged to project into openings provided therefor in the contiguous breast end wall portions whereby said closure member is releasably locked in place to be removable as a unit, at will, and is hingedly supported at its opposite end corner portions at either side when only the bolts at the other side are retracted from the openings in the contiguous wall portions, and reversely when only the other bolts are retracted.
